TELESCOPING ANTENNA ELEMENT

Edward Finkel, New York, N.Y., assignor to JFD
Electronics Corporation, Brooklyn, N.Y.

Filed Oct. 28, 1970, Ser. No. 22,925

Term of patent 14 years

Int. Cl. D14—03

U.S. Cl. D26—14

FIG. 1 is an elevational view of a telescoping antenna element showing my new design;

FIG. 2 is a top plan view of the telescoping antenna element of FIG. 1 looking in the direction of arrows 2—2; and

FIG. 3 is a sectional view of the telescoping antenna element of FIG. 1 looking in the direction of arrows 3—3.

I claim:

The ornamental design for a telescoping antenna element, as shown.
